 tion of New York

Filed June 29, 1964, Ser. No. 378,580
 9 Claims. (Cl. 137—13)

This invention relates to the transportation of mineral oils and more particularly to the pipeline transportation of mineral oils at temperatures at or near their pour points.

The transportation through pipelines of highly viscous mineral oils such as petroleum crude oils and shale oils in relatively cold weather has heretofore presented great difficulties. Many naturally occurring crude oils and shale oils become semisolids at low temperatures due to the presence of solid particles of wax, asphaltenes or resins which grow together at points of contact to form a structural matrix. This property of these oils is characterized by the ASTM (American Society for Testing Materials) pour point which is that temperature below which the oil will not pour from a standard container under certain specified conditions. See W. L. Nelson, Petroleum Refinery Engineering, McGraw-Hill Book Co., Inc., Fourth Edition 1958, pages 26 and 27.

The pour point has been accepted by pipeline engineers as the controlling factor of pipeline flow. Thus, where the normal temperature of a mineral oil is less than its pour point, it has been the practice to depress the pour point below the normal temperature by the use of additives such as light hydrocarbons or to heat the oil to a temperature above its pour point prior to pipelining. In fact, even in those cases where a mineral oil is normally a few degrees above its pour point it has been customary in pipeline operations to heat the oil or to dilute it by adding light hydrocarbons. Both of these practices are expensive and inconvenient. The former practice requires the installation of heating equipment at intervals along the pipeline and, in addition, steps must be taken to insulate the pipeline against heat loss. The latter practice may require that the diluent fluid be separated from the crude oil at the terminal point. In addition, the use of a diluent is practical only in those localities where a sufficient supply of light hydrocarbons is available.

It is an object of this invention to overcome the difficulties involved in the transportation by pipeline of relatively viscous mineral oils and to provide a method whereby such oils may be transported without the use of additives or the unnecessary use of heating equipment.

This invention is based upon the discovery that a mineral oil exhibiting pour-point characteristics may be transported through a pipeline at a temperature below or at the pour point at rates which approach, and in some cases even exceed, the rates possible when the oil is above its pour point. Thus, in carrying out the invention, a mineral oil is transported through a pipeline extending from a shipping point to a terminal point at a temperature near its pour point and under certain conditions of flow rate and pipeline diameter. In a further aspect of the invention, an oil which normally is at a temperature above or below its pour point is brought to a temperature near the pour point before pumping it through the pipeline under the aforesaid conditions.

For a better understanding of the invention, reference may be had to the following detailed description and to the drawing which shows a series of curves illustrating the advantages which may be obtained by the pipeline transportation of a mineral oil at or near its pour point.

In order to illustrate the invention, reference is made to the results of tests carried out on a shale oil in order to determine its flow characteristics at varying tempera-

tures in a pipeline. The physical properties of this shale oil are set forth below in Table I.

TABLE I

5	Specific Gravity at 60° F.	9377
	ASTM Distillation:	
	Initial Boiling Point	° F. 244
	48% Cracked	° F. 664

From the tests it was possible to determine the pressure gradients in pounds per square inch (p.s.i) per thousand feet of horizontal pipeline necessary to move the shale oil through the pipeline at different temperatures and flow rates. These pressure gradients in p.s.i per thousand feet for 15½", 12½" and 10½" I.D. pipes are set forth in Tables II, III, and IV, respectively. The flow rates are given in units of 1000 barrels per day wherein 1 barrel equals 42 U.S. gallons.

TABLE II—15½" I.D. PIPE

Temp., ° F.	Flow Rate (1,000 Bbls. per Day)						
	65	72	80	90	95	98	100
30	10.9	11.1	11.3	11.6	11.8	11.9	11.9

100	.30	.38	.40	.50	.57	.59	.62

The data set forth in Tables II, III, and IV show, surprisingly enough, that heating the shale oil above the pour point does not appreciably enhance the pumpability of the oil at the rates likely to be encountered in pipeline operations. More particularly, the data set forth in Table II shows that at rates of from 65,000 to 100,000 barrels

per day for the 15 $\frac{1}{4}$ " pipe, the pressure drop at the pour point (80° F.) is for the most part as low as, and in many cases lower than, the pressure drop at 90° F. or even at 100° F. For example, at a flow rate of 72,000 barrels per day (Table II), the pressure drop at the pour point is .21 p.s.i. per thousand feet of line; whereas the pressure drop is .22 p.s.i. at a temperature of 90° F. or a temperature of 100° F.

In some instances, a slight decrease in pressure gradient can be obtained by heating the oil to a temperature above the pour point. For example, at a flow rate of 100,000 barrels per day through the 15 $\frac{1}{4}$ " pipe, the pressure gradients per thousand feet at 90° F. and 100° F. are .40 p.s.i. and .37 p.s.i., respectively, as compared with a pressure gradient of .42 p.s.i. per thousand feet at the pour point. However, the decreases are so small, e.g., less than 5 percent due to heating the oil from 80° F. to 90° F., that the benefits obtained due to the reduced pumping requirements would in most cases be offset by the expense involved in installing and operating the necessary heating system.

From an examination of the above-noted and other data set forth in Tables II, III, and IV, it is apparent that little or no economic benefit can be gained by heating the oil to a temperature above its pour point. In fact, it is advantageous under certain conditions to cool an oil which is normally at a temperature above its pour point down to the pour point. For example, for the 15 $\frac{1}{4}$ " pipe, cooling the oil from 90° F. to 80° F. will result in a 30 percent decrease in the pressure gradient for a flow rate of 90,000 barrels per day.

A portion of the data set forth in Table II is illustrated in the drawing where the oil temperature (T) in degrees Fahrenheit is plotted against the log of the pressure gradient (ΔP) in pounds per square inch per thousand feet. With reference to the drawing, curves 1-7 show the relationship between pressure drop and temperature in the range of 50° F. to 100° F. for flow rates of 65,000, 72,000, 80,000, 90,000, 95,000, 98,000, and 100,000 barrels per day, respectively. As shown in the drawing, at flow rates within the range of 72,000 barrels per day (curve 2) to 98,000 barrels per day (curve 6), the pressure drop at the pour point is less than the pressure drop at the temperature 10° F. above the pour point, i.e., 90° F. Similar ranges also exist for the 12 $\frac{1}{4}$ " pipe (Table III) where the limits are 48,000 and 65,000 barrels per day and the 10 $\frac{1}{4}$ " pipe (Table IV) where the limits are 34,000 and 44,000 barrels per day. These ranges expressed in terms of the ratio of flow rate in thousands of barrels per day (Q) to the square of the pipe diameter in inches (D^2) are .31-.42, .32-.43, and .32-.42 for the 15 $\frac{1}{4}$ ", 12 $\frac{1}{4}$ ", and 10 $\frac{1}{4}$ " pipes, respectively. From this it can be seen that where the ratio Q/D^2 is within the range of .32-.42, a reduction in pressure gradient can be achieved by cooling the oil to the pour point. Conversely, where the oil normally is at or below the pour point, no advantage results from heating the oil to a temperature above the pour point when the ratio Q/D^2 is in the range of .32-.42.

The test results described above show that under the specified conditions of flow rate and pipe diameter, optimum results are obtained by flowing the oil through the pipeline at its exact pour point. However, it will be recognized that some latitude must be allowed in actual operations due to the difficulties involved in rigidly controlling the temperature of the oil. Moreover, at temperatures in the vicinity of the pour point, the change in pressure gradient with temperature is much less than at some temperatures further from the pour point. For example, in all of the cases represented by curves 1-7 of the drawing, the pressure gradient decreases with increasing temperature up to the pour point with the greatest relative reduction occurring between about 60° F. to 75° F. Within 5° F. of the pour point, the rate of pressure gradient reduction with increasing temperature is much less

than that within the aforementioned range. Therefore, in accordance with the invention, the oil is transported through the pipeline at a temperature within at least 5° F. of its pour point and preferably at the pour point or as near thereto as practical.

In the application of the invention to the pipeline transportation of a mineral oil, the oil is transferred to a pipeline which extends from a shipping point, e.g., a storage facility or a processing installation such as a shale-oil extraction plant, to a suitable terminal point. A first pumping station may be located adjacent the shipping point and, if necessary, additional pumping stations may be located at intervals along the pipeline in a manner well known to those skilled in the art. The oil is flowed from the shipping point through the pipeline to the first pumping station and then pumped through the pipeline at a temperature within 5° F. of its pour point and at a flow rate such that the ratio Q/D^2 is within .32-.42.

If the oil has a pour point sufficiently near its basic tem-

perature, i.e., the normal temperature of the oil at the shipping point, the oil can be pipelined without the use of heating or cooling equipment. However, in those cases where the basic temperature of the oil is significantly above or below the pour point, the temperature of the oil is adjusted to a temperature within 5° F. of the pour point and preferably to the pour point. Thus, in the application of the invention to a mineral oil having a basic temperature lower, particularly by more than 5° F., than its pour point the oil is heated to within 5° F. of the pour point in order to gain a reduction in pressure drop through the pipeline. Preferably, the oil is not heated above the pour point, since no further pressure gradient reduction results where the ratio Q/D^2 is within the range of .32-.42. In this embodiment of the invention, the pipeline may be insulated or heating stations may be installed at intervals along the pipeline in order to maintain the oil at a temperature within 5° F. of its pour point.

As noted above, a further aspect of the invention involves the pipeline transportation of a mineral oil having a pour point less than its basic temperature. In this case, the oil is cooled to within 5° F. of its pour point, and preferably to a temperature not less than the pour point, and pumped through the pipeline at a flow rate such that the ratio Q/D^2 is within the range of .32-.42. If necessary in maintaining the oil at or near its pour point, the oil may be passed through cooling stations located at intervals along the pipeline. Also, the pipeline may be suitably insulated in the event the ambient temperature is significantly higher than the pour point of the oil.

Having described specific embodiments of the invention, it is understood that further modifications may become apparent to those skilled in the art and it is intended to cover all such modifications as fall within the scope of the appended claims.

We claim:

1. In a method of transporting a mineral oil, the steps of flowing said mineral oil through a pipeline extending from a shipping point to a terminal point at a temperature within 5° F. of its pour point in at least a portion of said pipeline, and maintaining the flow rate of said oil such that the ratio of said flow rate in thousands of barrels per day to the square of the inner diameter in inches of said pipeline is not less than .32 nor more than .42 for said portion of said pipeline.

2. The method of claim 1 wherein said mineral oil is at its pour point in said portion of said pipeline.

3. In a method of transporting a mineral oil having a pour point different from its basic temperature, the steps of adjusting the temperature of said mineral oil in the direction of its pour point to a temperature within 5° F. of its pour point, flowing said mineral oil through a pipeline extending from a shipping point to a terminal point at a temperature within 5° F. of its pour point in at least a portion of said pipeline, and maintaining the flow rate of said oil such that the ratio of said flow rate in thou-

sands of barrels per day to the square of the inner diameter in inches of said pipeline is not less than .32 nor more than .42 for said portion of said pipeline.

4. In a method of transporting a mineral oil having a pour point less than its basic temperature, the steps of cooling said mineral oil from said basic temperature to a temperature within 5° F. of its pour point, flowing said oil through a pipeline extending from a shipping point to a terminal point at a temperature within 5° F. of its pour point in at least a portion of said pipeline, and maintaining the flow rate of said mineral oil such that the ratio of said flow rate in thousands of barrels per day to the square of the inner diameter in inches of said pipeline is not less than .32 nor more than .42 for said portion of said pipeline.

5. The method of claim 4 wherein said mineral oil is cooled to a temperature in the range of its pour point to 5° F. above its pour point.

6. The method of claim 4 wherein said mineral oil is cooled to its pour point.

7. In a method of transporting a mineral oil having a

pour point greater than its basic temperature, the steps of heating said mineral oil from said basic temperature to a temperature within 5° F. of its pour point, flowing said mineral oil through a pipeline extending from a shipping point to a terminal point at a temperature within 5° F. of its pour point in at least a portion of said pipeline, and maintaining the flow rate of said oil such that the ratio of said flow rate in thousands of barrels per day to the square of the inner diameter in inches of said pipeline is not less than .32 nor more than .42 for said portion of said pipeline.

8. The method of claim 7 wherein said mineral oil is heated to a temperature in the range of its pour point to 5° F. below its pour point.

15 9. The method of claim 7 wherein said mineral oil is heated to its pour point.
